UNITED STATES PATENT OFFICE.

FREDERICK W. COEN, OF CHICAGO, ILLINOIS.

GAS-ENGINE.

SPECIFICATION forming part of Letters Patent No. 575,878, dated January 26, 1897.

Application filed May 14, 1896. Serial No. 591,465. (No model.)

To all whom it may concern:

Be it known that I, FREDERICK W. COEN, a citizen of the United States, residing at Chicago, in the county of Cook and State of Illinois, have invented a new and useful Improvement in Gas-Engines, of which the following is a specification.

My invention relates to improvements in gas-engines, more especially of the class in which an explosion takes place during the ordinary running of the engine once in every second reciprocation of the piston.

My object is to provide a gas-engine having novel and improved automatic exhaust-controlling and speed-governing mechanisms, all to the end of simplifying the construction and operation of the engine and of rendering it compact, powerful, particularly steady in operation, and durable.

In the drawings, Figure 1 is a side elevation of my improved engine with the crank-shaft in section; Fig. 2, a broken plan view of the engine, showing the cylinder and its attendant parts in section; and Fig. 3, a vertical section taken on line 3 of Fig. 2.

The drawings show only so much of the engine as is necessary to illustrate my present improvements.

A is the engine-frame, B the crank-shaft journaled therein, and C a jacketed cylinder. The space between the concentric walls of the cylinder has inlet and outlet pipes t t' , respectively, for the circulation of a cooling fluid, such as water or cold air. The cylinder is open at its forward end, and at its rear end is closed by a cylinder-head C'. Extending through the jacket at the lower side of the cylinder, in the position shown, is a preliminary exhaust or vent port s, communicating with a pipe or passage s', and in the cylinder-head is an exhaust-port r, communicating with a pipe or passage r'. The passages s' r' communicate at a coupling q. In the cylinder-head C' are concentric ports p n. The outer port p communicates with a gas-supply passage p', and the inner port n communicates with an air-supply passage n'. At the port r in the cylinder or explosion chamber C' is a valve m on a stem m', passing through a guide in the passage r' to extend beyond the rear end of the engine. Seating upon the concentric ports n p in the chamber C' is a

valve l on a stem l', which passes through a guide in the passage n' and beyond the rear end of the engine, as shown. Fastened upon the cylinder-head between the stems m' l' is an arm k. Resting against the end of the arm k is a rod or spring k', fitting at its opposite ends loosely around the valve-stems m' l'. At the stem l' the spring k' rests against a collar l', fixed to the said stem, and confined between the spring k' and adjacent surface of the cylinder-head is a coiled spring l'', which tends normally to maintain the valve l closed.

Mounted in guides x x' x'' on the side of the cylinder is a longitudinally-movable bar or rod D, secured at its rear end to the end portion of the exhaust-valve stem m', being confined thereon between a collar m'' and a nut m''. On the rod D between the guides x x' is a collar D', and confined upon the rod between the guide or bearing x and collar D' is a spring D'', which tends to force the rod in the direction to the right in Fig. 2 until the collar D' strikes the guide x'. Thus the tendency of the spring D'' is to maintain the rod D in a forward position and the exhaust-valve m normally open. The forward end portion of the rod D at its under side is cut away, as shown in Fig. 1, to produce the guide-surface D' and notch or shoulder D'.

Fixed upon the crank-shaft B, in the position shown, is a cam E, having the circular face E' and straight face E''. F is a lever pivoted at its lower end portion to the side of the frame A at e. Journaled upon the upper end of the lever F is an antifriction-wheel e', and fixed to and extending forward from the upper end of the lever F is an arm F', having a laterally-projecting finger e''. F'' is a preferably spring-finger pivotally mounted at its forward end upon the side of the arm F' and resting between its ends normally upon the finger e''. A spring F''' is attached at one end to the lever F, and at its opposite end to a screw i, passing through a guide i' on the side of the frame A and provided with a thumb-screw i''. The tendency of the spring F''' is to press the lever at its roller e' against the cam E. In the rotation of the crank-shaft when the roller e' is at the center of the flat surface E'' the arm F' extends in the horizontal plane and tends to raise the spring-

finger F^2 to the plane of the surface D^3 , while when the roller e' is engaged by the surface E' of the cam the lever F is pushed backward to the position shown in Fig. 1.

5 The drawings show the moving parts of the gas-engine in the position wherein the piston is about to move in the forward direction to draw in a charge of gas and air. In this movement the suction action of the piston opens 10 the valve l against the resistance of the spring b^3 and draws in gas and air from the supply-passages $n' p'$. As the fluids enter the chamber C^2 they become thoroughly mixed. While the tendency of the spring D^2 on the rod D is 15 to maintain the exhaust-valve m open, the engagement of the surface E' of the cam with the roller e' on the lever F has thrust the latter forward, causing the spring-finger F^2 to engage the shoulder D^4 on the rod D , thrust the 20 latter backward against the resistance of the spring D^2 , and closed the valve m . The engagement of the surface E' with the roller e' continues during about two-thirds of a complete revolution of the crank-shaft, so that 25 the rod will be kept in the position of closing the valve m from the time the piston starts forward until it has again moved in the backward direction about one-third the distance of its traverse. The piston moves from the 30 position shown to a point wherein it uncovers the vent or initial-exhaust port s ; but owing to the fact that the said port is at the lower side of the cylinder none of the gas will escape. In the backward stroke of the piston the air 35 and gas are compressed, and when one-third of the distance is traversed the surface E' of the cam E will pass the roller e' , whereby the latter is retracted by the spring F^3 to the surface E^2 , thus releasing the finger F^2 from engagement with the rod D and causing it to 40 rest upon the finger e^2 . The exhaust-valve m will still remain closed against the resistance of the spring D^2 under the force of the compressed fluid in the chamber C^2 .

45 On the cylinder C is an igniter G , which may be of any suitable form, and therefore unnecessary to illustrate in detail in the present connection.

When the piston again reaches the position 50 shown in the figures, which is the rear end of its traverse, the explosion of the gas in the chamber C^2 occurs, driving the piston forward. As soon as the piston uncovers the port s a preliminary exhaust or venting takes 55 place through the pipe s' , thus relieving the pressure in the chamber to an extent which permits the spring D^2 to move the rod D and open the valve m . During the time that the valve m is held closed under the pressure in 60 the chamber C^2 the rod D is held in its backward position and the shoulder D^4 is out of the path of the finger F^2 . Thus during the next movement of the piston in the backward direction following the explosion the valve 65 m will be maintained open by the spring D^2 . While the valve m is thus maintained open the collar m^2 on the stem m' bears against the

rod or spring k' , thereby pressing the opposite end of said rod or spring against the collar b^2 and holding the valve l closed. In the 70 following forward movement of the piston the valve l will thus be maintained closed or locked and air will be drawn in through the port r and then discharge through the same to clean out the cylinder. In the second 75 backward movement of the piston following the period of explosion, the valve m being open and the rod D in its forward position, the finger F^2 will engage the shoulder D^4 , push the rod D backward, and close the valve m 80 just as the piston reaches the initial position shown in the drawings.

It will be understood that owing to the strip or spring k' the inlet-valve l is locked and cannot open when the exhaust-valve m is open, 85 and that the valve m , owing to the spring D^2 , is normally open, being closed only when the rod D is engaged and pushed backward by the finger F^2 . The movement of the lever F under the action of the cam E reciprocates the finger F^2 longitudinally, and the up-and-down oscillation of the arm F' and its finger e^2 in the movement of the lever F causes the finger F^2 to be raised to the plane of the shoulder D^4 when the roller e' is at or near the center of 95 the surface E^2 of the cam and to fall below the said plane unless held raised by engagement with said shoulder. In order that the finger F^2 may engage the shoulder D^4 and close the valve m , the roller e' must glide upon 100 the surface E^2 to about the center of the latter, and this will only be the case when the cam rotates at less than a predetermined speed, depending upon the tension of the spring F^3 . When the cam rotates at a higher 105 rate of speed, the roller e' will be caused to jump across the surface E^2 of the cam, so that the finger F^2 will not be retracted sufficiently to engage the shoulder D^4 . The lever F and attendant parts thus operate as a governor 110 mechanism to regulate the explosions and consequent speed of rotation of the crank-shaft. By means of the thumb-nut i^2 the spring F^3 may be tensioned to regulate the pressure of the roller e' against the cam. The 115 greater the tension of the spring F^3 the higher the speed at which the crank-shaft may revolve without causing the roller e' to jump the cam-surface E^2 . By regulating the tension of the spring F^3 , therefore, the governing 120 mechanism may be regulated to hold the engine down to a desired speed by causing the valve m to remain open and the valve l to remain closed to prevent explosions during one-half, one, or more of the periods when explosions should occur.

When a gas-engine is located in the room of a building, it is usual to provide an exhaust-pipe extending to the roof to carry off the products of combustion. In the present 130 case such a pipe will be connected to the coupling q , and in order to prevent the piston, when the valve m is open, from sucking back the products of combustion from the exhaust-

pipe I provide a port q' in the coupling q , fitted with a valve q^2 , which opens inward and is held to its seat by a light spring q^3 . The valve q^2 will prevent products of combustion 5 from being discharged into the room and will open to let in fresh air when the valve m is open and the piston moves forward.

My improvements afford a safe and positive means for insuring the proper opening and closing of the inlet and exhaust valves and for governing the speed of the engine. The mechanism is simple and durable and, while always performing its function in a satisfactory manner, is not liable to get out of order.

15 My improved governor mechanism may be employed to open and close a gas-inlet valve instead of the exhaust by connecting the rod or bar D with said valve and arranging the parts as required. In this way the speed of 20 the engine will be governed by the opening and closing of the gas-supply instead of the exhaust, as described.

The outlet-valve m I term a "normally open" valve, for the reason that the spring 25 D^2 , which is a permanent attachment to the valve, maintains the latter open except when the finger F^2 acts to close the valve against the resistance of the spring. The normal tendency of the valve m is to remain open, 30 while that of the valve l is to remain closed, and their normal tendencies are overcome only by extraneous forces, such as that under the action of the finger F^2 in the one instance and of the inflowing explosive mixture in the other.

35 Although I prefer to construct my improvements throughout as shown and described, they may be modified in the matter of details of construction without departing from the spirit of my invention as defined by the claims.

40 What I claim as new, and desire to secure by Letters Patent, is—

1. In a gas-engine, the combination with the crank-shaft and piston, of a cylinder having a gas-inlet port, an exhaust-port and a vent-port opened and closed by the piston, a normally closed valve at the said inlet-port, a normally open valve at the said exhaust-port, and closing means for said exhaust-port valve actuated from the said crank-shaft, substantially as and for the purpose set forth.

45 2. In a gas-engine, the combination with the crank-shaft and piston, of a cylinder having a gas-inlet port, an exhaust-port and a vent-port opened and closed by the piston, a normally closed valve at the said inlet-port, a normally open valve at the said main exhaust-port, a connection between the said valves operating to lock the inlet-port valve 50 against opening when the exhaust-port valve is open, and closing means for the said exhaust-port valve actuated from the said crank-shaft, substantially as and for the purpose set forth.

55 3. In a gas-engine, the combination with the crank-shaft and piston, of a cylinder hav-

ing a gas-inlet port, an exhaust-port, and a vent-port opened and closed by the piston, a normally closed valve at the said inlet-port, a valve at the exhaust-port, spring mechanism 70 connected with the said exhaust-port valve and tending to hold the same normally open, a cam upon the crank-shaft, and governor mechanism between the said cam and spring mechanism operated by the said cam 75 to move the said spring mechanism and close the exhaust-port valve intermittently, substantially as and for the purpose set forth.

4. In a gas-engine, the combination with the crank-shaft and the cylinder provided 80 with an exhaust-port, of a normally open valve at said exhaust-port, closing means for said valve, a cam on the crank-shaft and governor mechanism actuated by the said cam to intermittently engage and operate the said 85 valve-closing means to close said valve and means for regulating the pressure of engagement between the cam and governor, whereby when the cam rotates faster than a predetermined speed, the governor will jump upon the 90 cam and thereby fail to engage and operate the valve-closing means, substantially as and for the purpose set forth.

5. In a gas-engine, the combination with the crank-shaft and the cylinder provided 95 with an exhaust-port, of a valve at said exhaust-port, a reciprocatory bar connected with the said exhaust-port valve, a spring at the bar tending to hold the same normally in the position of opening said valve, a cam on 100 the crank-shaft, governor mechanism actuated by the said cam to intermittently engage and move said bar to close said valve, and means for regulating the pressure of engagement between the cam and governor, whereby 105 when the cam rotates faster than a predetermined speed, the governor will jump upon the cam and thereby fail to engage and move the said bar, substantially as and for the purpose set forth.

6. In a gas-engine, the combination with the crank-shaft and the cylinder provided with an exhaust-port, of a valve at said exhaust-port, a reciprocatory bar connected with the said exhaust-port valve, a spring at 115 the bar tending to hold the same normally in the position of opening said valve, a cam on the crank-shaft, governor mechanism actuated by the said cam to intermittently engage and move said bar to close said valve, comprising a pivotal lever F provided with the cam-engaging roller and a swinging rod-engaging finger F^2 , a spring pressing the lever at its roller against the cam, and tensioning 120 means for the spring, the parts being constructed and arranged to operate substantially as and for the purpose set forth.

7. In a gas-engine, means for governing the opening and closing of an inlet or exhaust valve, comprising a cam rotated by the crank-shaft, a bar connected with the valve and movable to open and close the same, a spring at 130

the bar holding the same normally in one position, and governor mechanism actuated by the said cam to intermittently engage and move said bar against the resistance of its
5 spring, and means for regulating the pressure of engagement between the cam and governor, whereby when the cam rotates faster than a

predetermined speed, the governor will jump upon the cam and thereby fail to engage and move the bar, substantially as described.
